UNITED STATES PATENT OFFICE.

ORLANDO W. NORCROSS, OF WORCESTER, MASSACHUSETTS.

CONCRETE FLOOR CONSTRUCTION.

1,133,658.

Specification of Letters Patent. Patented Mar. 30, 1915.

Application filed September 30, 1914. Serial No. 864,349.

To all whom it may concern:

Be it known that I, ORLANDO W. NORCROSS, a citizen of the United States, residing at Worcester, in the county of Worcester 5 and State of Massachusetts, have invented a new and useful Concrete Floor Construction, of which the following is a specification.

The principal objects of this invention 10 are to provide an inexpensive and practical concrete construction for a floor in which each rectangle of concrete formed between the four posts or columns will in itself constitute an arch capable of resisting immense 15 strains, and having a maximum of strength with a minimum amount of metal reinforcement, and in which the different units of the floor can be arranged entirely separate from each other and will not in any way 20 depend upon one another, that is, each rectangular unit will be self-sustaining and each one would stand the strain for which it is built, even if it stood alone. In this way each section can be built separately 25 if desired and none of the complication of connecting one section to the others before the concrete is applied is necessary. I also provide a construction for this purpose in which strong and relatively inexpensive 30 supporting means is employed for the concrete, this supporting means constituting a continuous band around each concrete arch which would have to give way at all points and crush the concrete in order to yield 35 anywhere; and I also provide a convenient and inexpensive way of firmly securing these irons together and strengthening the structure.

The invention also involves other features 40 of construction as will appear hereinafter. Reference is to be had to the accompanying

drawings in which—

Figure 1 is a plan of a portion of a floor 45 constructed in accordance with this invention and showing only one of the concrete slabs; Fig. 2 is a sectional view on the line 2—2 of Fig. 1; Fig. 3 is a plan of another embodiment of the invention, and Fig. 4 is a plan of another form.

Many plans have been proposed for making 50 concrete floors. The present invention relates to the type in which each unit of the floor, preferably of rectangular form resting at its four corners on columns, is a separate unit in itself, and is provided with a surrounding band of metal connected se-

curely together so as to form a continuous surrounding structure and resting on the four columns. In this way this band of metal which is relatively strong and rigid, 60 although formed of tie members, resists forces tending to spread the four sides of each concrete member by transmitting these strains to the columns and by interposing a solid body of concrete from each column 65 to the center of the rectangle which would have to be crushed in order to distend the other members at their centers. More in detail, I mean by this that any force tending to push out the centers of the four iron ties 70 surrounding the concrete rectangle will be resisted by the connection of these ties with each other at the corners where they meet at the columns. In order to force the center of one of the ties outwardly the corners 75 would have to move inwardly toward the center of the rectangle. The latter motion is prevented by the solid body of concrete which extends of course from each corner to the center of the concrete member, as it 80 does to all parts thereof. In this way the well known great resistance of the body of concrete to a crushing strain is brought into full effect for the purpose of rendering each element independent and self-sustaining. 85 The especial object of this invention is to provide improved means for connecting these ties.

Referring now to Figs. 1 and 2 of the drawings it will be seen that the floor is 90 designed to be supported by columns, and two forms A and A' are shown. The former simply supports the floor and the other supports the floor at another point and extends up through it for the purpose of 95 supporting a floor or roof above. In either case the column is provided with a plate a and a' on which the floor is directly supported.

For the purpose of carrying the concrete 100 floor a series of ties shown in the form of angle irons B is employed, radiating from the center of each column. These angle irons preferably are arranged in pairs at right angles to each other and with one 105 flange of all the angle irons located in a horizontal plane, the other flange in each case being arranged vertically.

Over the column A the angle irons can be mitered off at their ends so as to rest 110 on the cap plate a on the column and meet each other at a point directly over the col-

umn. For the purpose of securing them together, gusset plates C are employed, riveted to the horizontal flanges of the angle irons. These plates are arranged in horizontal position. Each of these plates secures two adjacent angle irons located at an angle to each other. They are further secured by angle pieces D at the meeting edges of the angle irons riveted to them or otherwise firmly secured. It will be seen that these fastening devices secure the two angle irons adjacent to each other and also the two located at ninety degrees. In order to secure the ties together on opposite sides 15 of the column a series of thin metal tie bars E are employed. The centers of these ties are placed over the ends of one pair of angle irons in horizontal position and their ends are bent around at ninety degrees 20 to a vertical position so that they can be riveted at e to the vertical flanges of the angle irons. Thus they tie up the angle irons at a distance from the column on which their ends are supported. In this 25 way each angle iron is firmly secured to the one next to it and at right angles from it, and is also firmly secured to the opposite angle iron in alinement with it on the other side of the column. Furthermore, by ex- 30 tending these rivets e through the two angle irons those of each pair are also firmly secured together. It is to be observed that the vertical flanges of these angle irons are spaced apart slightly and a cross-shaped 35 spacing block F is put in place over each column A to limit this spacing and to keep the angle irons in proper relative position. When a column as A' extends up through the floor the same principle is employed, 40 but in this case the angle irons B of course cannot meet each other, but they are cut off straight across at their inner ends where they come against the column. Their inner ends come together but are not secured di- 45 rectly together by anything equivalent to the angle pieces D. However, gusset plates C' are employed similar to the gusset plates C, but of a different shape. Moreover the bars E' which correspond with the bars E 50 are treated in the same way, but, of course, have to be spread apart to pass the column as indicated at the right in the drawings. These parts having been put in position the concrete G is molded between them. In 55 this way each solid rectangular body of concrete firmly engages the upright flanges of the angle irons and rests on the horizontal flanges. These supports or angle irons B are an efficient means for holding up the 60 concrete floor. Furthermore, the ties greatly assist in strengthening the structure and holding the angle irons in proper position at a distance from their points of support. However, a very important fea- 65 ture is the fact that four of these ties B, se-

cured together at the corners at which they are supported, entirely surround the concrete monolith G and in effect constitute a surrounding band that prevents distortion of the concrete structure at any point. The 70 reason for this is that with this surrounding band in place, it would be necessary to crush a part of the concrete slab in a direction in its own plane, in order to get the band to yield in an outward direction at any 75 point.

In Fig. 3 the same principle is carried out, but woven wire reinforcements H are laid along the edges of each rectangular space before the concrete is poured to reinforce 80 the same. They rest on the ties D. In Fig. 4, this kind of reinforcement is replaced by a single steel cable K surrounding each concrete slab but embedded in it.

Although I have illustrated and described 85 only a few forms of the invention I am well aware that other modifications can be made therein by any person skilled in the art without departing from the scope of the invention as expressed in the claims. Therefore, I do not wish to be limited to the exact 90 structures shown, but

What I do claim is:—

1. A supporting structure for a concrete 95 floor, comprising a series of supports radiat- 100 ing from a point in a horizontal plane and connected together at their adjacent ends, and a series of tie members each secured at its ends to two of said supports below the tops thereof, that are located on opposite 105 sides of said point and resting at their centers on the tops of supports located at an angle to those to which said tie members are secured and at the same height.

2. A supporting frame for a concrete floor 110 comprising horizontal irons having vertical 115 flanges radiating from a point, and flat metal bars, each secured at its ends in verti- 120 cal position flat against the vertical flanges of two of said irons that are in alinement and twisted and resting at its center in horizontal position on the tops of others of said irons.

3. A supporting structure for a concrete 125 floor comprising a column, a plurality of 130 angle irons radiating from the column in a plane and placed with one flange horizontal and the other vertical, and a series of flat bars each arranged with its ends vertical and secured against the vertical flanges of two opposite angle irons at a distance from the column, the central part of each bar lying horizontally over the tops of the ends of others of said angle irons.

4. A support for a concrete floor comprising a column, a plurality of angle irons ar- 135 ranged in pairs radiating therefrom and each placed with one flange vertical, hori- 140 zontal gusset plates for securing the ends of said angle irons together at the column, and

a series of pairs of flat bars each arranged with its ends vertical and secured to the vertical flanges of two of said angle irons which are in alinement with each other, the central part of each of said bars lying horizontally over the tops of others of said angle irons.

5. A supporting structure for a concrete floor comprising a column, a plurality of 10 angle irons radiating from the column in a plane and placed with one flange horizontal and the other vertical, the inner ends of said angle irons resting on the column, a series 15 of flat bars each arranged with its ends vertical and secured against the vertical

flanges of two opposite angle irons at a distance from the column, the central part of each bar lying horizontally over the tops of the ends of others of said angle irons, and a series of vertical angle pieces riveted to the 20 ends of said angle irons for securing them together over the column.

In testimony whereof I have hereunto set my hand, in the presence of two subscribing witnesses.

ORLANDO W. NORCROSS.
